UNITED STATES PATENT OFFICE.

LLOYD G. COPEMAN, OF FLINT, MICHIGAN, ASSIGNOR TO COPEMAN LABORATORIES COMPANY, OF FLINT, MICHIGAN, A CORPORATION OF MICHIGAN.

METHOD OF TABLE-TOP CONSTRUCTION.

Original application filed March 24, 1925, Serial No. 16,304. Divided and this application filed September 16, 1925. Serial No. 56,628.

This invention relates to a table top construction and is more particularly directed to the method of construction wherein an artificial stone moulding is cast to a slab and a silencing pad is secured to said slab inside of said moulding.

This is a divisional application, the subject matter being originally contained in my copending application Serial No. 16,304, filed March 24, 1925. In this prior application the silencing pad was first secured to the slab and the moulding cast therearound, while in this application the moulding is first secured to the slab and then the silencing pad is secured to the slab inside of said moulding.

In the drawings:

Fig. 1 is a perspective view of the table top.

Fig. 2 is a section taken on the line 2—2 of Fig. 1.

Fig. 3 is a vertical section through a mould showing the process of casting the moulding to the table top.

Fig. 4 is a sectional view of the top slab construction showing the silencing pad about to be fitted into the recess inside of said moulding.

Fig. 5 is a partial plan view of a modified form of construction in which the silencing pad is composed of a plurality of small sections fitted together.

Fig. 6 is a detail section showing another modified form of construction wherein the moulding is cast-united to the turned-up edges of the sheet metal cover which is secured to the wood slab.

The first step in this process is to secure a sheet metal cover *a* by means of screws *c* or other suitable fastening devices to a slab *b* preferably composed of some fibrous material such as wood, so as to be light in weight but yet possessing great tensile strength. This slab, with the metal cover secured thereto, is then inserted into a mould *d*, the brackets *e* centering said slab in the mould in spaced relation with respect to the side walls of the mould. Large headed nails or screws *f* may be secured to the edge of the wood slab. An artificial stone mixture is now poured into the space between the slab and mould and I preferably use for this, an artificial stone such as oxy-chloride cement. When this stone mixture

is allowed to set the heads of said screws *f* are imbedded in the stone, thereby forming a moulding *g* which is secured or cast-united to the peripheral edge of the slab. The mould is arranged in such a way as to form a moulding which overlaps slightly the peripheral edge of said slab and provides a recess *h*. Observing Fig. 4 it will be seen how the bottom of this recess is formed of the slab, the metal cover *a* on the face of the slab absolutely preventing moisture of any sort from contacting with the wood portion of the slab, as after the silencing pad *i* is fitted in said recess it is quite likely that some moisture might leak past the joint between the pad and moulding.

Fig. 4 shows one large silencing pad fitted into the recess but obviously this silencing pad could be formed of a plurality of sections such as is shown in Fig. 5. Also if preferred, the edges of the metal cover *a* could be turned up as at *k* (see Fig. 6), the turned up edges bent back and being perforated as at *m* if so desired. Now when the stone moulding is cast about the slab this stone will flow through the perforations *m* and the moulding will be cast-united to the metal cover thus insuring a more perfect union between the moulding and the slab.

This silencing pad may be made by trowelling in a plastic composition which is allowed to set. This composition is preferably composed of 30% magnesium oxide (dry powder) by weight, 15% wood flour by weight, 10% of ground asbestos fibre by weight, 10% kieselguhr by weight and 40% silica by weight. To this dry mixture is added sufficient magnesium chloride in solution at 26 degrees Bé. specific gravity to reduce the mixture to a wet paste suitable for trowelling. This trowelled-in mass forms a silencing pad possessing practically the same qualities as the linoleum pad.

What I claim is:

1. A method of table top construction, which comprises the inserting of a slab in a mould in spaced relation with the sides of the mould, the casting of an artificial stone moulding about the peripheral edge of said slab, and the securing of a silencing pad thereto inside of said moulding.

2. A method of table top construction, which comprises the inserting of a wooden

slab in a mould in spaced relation with the sides of the mould, the casting of an artificial stone moulding about the peripheral edge of said slab, and the securing of a silencing slab thereto inside of said moulding and formed of one or more sections of linoleum fitted therein.

3. The method of constructing a composite table top which comprises casting a stone-like moulding around the edges and slightly over a side of a base member, and then placing a pad on the base member within the portions of the moulding which extend over the side of such base member.

4. The method of constructing a composite table top which comprises casting a stone-like moulding around the edges and slightly over a side of a base member, and then placing a pad on the base member within the over-lapping portions of the moulding which has a thickness substantially the same as that of the over-lapping portions.

5. The method of constructing a composite table top which comprises placing a base for the top in a mould, casting a stone-like moulding around the edges of the base member and slightly over a side thereof, and

then placing a pad on the side of the member which is slightly overlapped by the moulding.

6. The method of constructing a composite table top which comprises securing a protecting plate to a wooden base member, placing the base and its protecting plate in a mould, casting a stone-like moulding around the edges and slightly over the side of the protecting plate, and then placing a pad against the protecting plate and within the overlapping portions of the moulding.

7. The method of constructing a composite table top which comprises securing a metallic protecting member to a wooden base plate which has a part which extends in spaced relation to the edges of the base member, casting a stone-like moulding around the edges of the base member which covers both sides of the extending part of the metallic member and which is reenforced thereby, and then inserting a pad against the metallic protecting member and within the moulding.

In testimony whereof I affix my signature.

LLOYD G. COPEMAN.
